UNITED STATES PATENT OFFICE.

GILBERT L. CROWELL, JR., OF ARLINGTON, NEW JERSEY.

DESIGN FOR A HANDLE FOR A SPOON, FORK, OR SIMILAR ARTICLE.

SPECIFICATION forming part of Design No. 36,240, dated March 3, 1903.

Application filed September 8, 1902. Serial No. 122,634. Term of patent 14 years.

To all whom it may concern:

Be it known that I, GILBERT L. CROWELL, Jr., a citizen of the United States, residing at Arlington, county of Hudson, and State of New Jersey, have invented and produced a new, original, and ornamental Design for Handles for Spoons, Forks, or Similar Articles, of which the following is a description, reference being had to the accompanying drawings, which illustrate the design.

Figure 1 is a plan or elevation view of the front or obverse side of a spoon the handle of which embodies my design, the dotted lines showing how the handle may be applied to a fork. Fig. 2 is a similar view of the reverse or rear side of the spoon and handle. Fig. 3 is a cross-section on the line *a a* of Fig. 1.

The general outline of the handle is of the pandurate or fiddle-shaped order. Along the opposite edges of both sides of the handle are lines of fluting A, which terminate in the head of the handle in scroll-like ornamentations B. Parallel to these flutings is another set of flutings, which terminate at the bottom of the

scroll B. The ornamentation at the head of the handle consists of the termination of the inner flutings, the scrolls B, the panel D, and on the obverse side the alternately large and small drop-pieces C, and on the reverse side the shell-like ornamentation G, the flutings of which are concave. Along each of the opposite edges of both sides of the lower part of the handle are scrolls E, which form the termination of the lines F, which extend from the base of the spoon or fork. Between the termination-scrolls E on each side of the handle there is located the ornament H of general calyx form. On the reverse side is a scalloped or shell-like ornamentation J.

What is claimed as new is—

The ornamental design for the handle of a spoon, fork or similar article, substantially as shown and described.

GILBERT L. CROWELL, JR.
